Primary Examiner—James Gandy*Assistant Examiner*—Cathron B. Matta*Attorney, Agent, or Firm*—Nikaido, Marmelstein, Murray & Oram LLP**[57] CLAIM**

The ornamental design for a liquid dispenser, as shown and described.

DESCRIPTION

FIG. 1 is a front elevation view of a liquid dispenser showing my new design, the rear view being a mirror image; FIG. 2 is a right side elevation view thereof;

FIG. 3 is a front elevation view thereof, with the cap shown removed;

FIG. 4 is a right side elevation view of FIG. 3;

FIG. 5 is a left side elevation view of FIG. 3;

FIG. 6 is a right side elevation view of FIG. 3, with the arm shown in an alternate position;

FIG. 7 is a top plan view of FIG. 3; and,

FIG. 8 is a bottom plan view of FIG. 3.

The broken line showing of the cap in FIGS. 1 and 2 and the tube in all of the above figures is for illustrative purposes only and forms no part of the claimed design.
